CLAIM

The ornamental design for a tumbler lid, as shown and described.

DESCRIPTION

FIG. 1 is a top perspective view of our new design; FIG. 2 is a bottom perspective view thereof; FIG. 3 is a top view thereof; FIG. 4 is a bottom view thereof; FIG. 5 is a front view thereof; FIG. 6 is a back view thereof; FIG. 7 is a cross-sectional view of the tumbler lid of FIG. 1 taken along line 7-7 in FIG. 5; FIG. 8 is a right side view thereof; FIG. 9 is a left side view thereof; FIG. 10 is an exploded top perspective view thereof; and, FIG. 11 is an exploded front view thereof. The broken lines in FIGS. 2 and 4 depict portions of the tumbler lid that form no part of the claimed design.
